UNITED STATES PATENT OFFICE.

WILBUR C. NORRIS, OF TIONA, PENNSYLVANIA.

STUFFING-BOX.

SPECIFICATION forming part of Letters Patent No. 783,644, dated February 28, 1905.

Application filed March 12, 1904. Serial No. 197,810.

To all whom it may concern:

Be it known that I, WILBUR C. NORRIS, a citizen of the United States, residing at Tiona, in the county of Warren and State of Pennsylvania, have invented new and useful Improvements in Stuffing-Boxes, of which the following is a specification.

This invention relates to stuffing-boxes; and it consists in certain improvements in the construction thereof, as will be hereinafter fully described, and pointed out in the claim.

The stuffing-box is particularly adapted for use in oil-wells in connection with the polished rod, and the structure shown is so arranged.

15 The invention is illustrated in the accompanying drawings as follows: Figure 1 shows a plan view of the structure; Fig. 2, a central section; Fig. 3, a section on the line 3-3 in Fig. 2, the view being from the bottom of 20 Fig. 3.

A marks the box proper, in which is arranged the packing-cavity. The box has the screw-thread α at its lower end, which is adapted to screw to a tubing-top, and the opening 25 α' , through which the polished rod passes. A packing B is shown in the packing-cavity. A follower C is arranged in this cavity and has a shoulder c , on which the spring D may rest. The spring D is an ordinary coiled 30 spring and is in such a position as to encircle a polished rod when operating. A cross-plate E has the opening e , through which the polished rod passes. It also has the perforation e' for the tightening-bolts and an annular 35 groove e^2 , in which the spring D is arranged.

The tightening-bolts F extend through the perforation e' and perforations α^2 in the flanges

A' of the box A. Adjacent to the perforations α^2 are the brace-shoulders α^3 . These tend to brace the flange α' and at the same time furnish 40 a locking means for locking the nuts f on the bolts F. This structure is a very simple but very efficient one. The cavity formed by the follower C is so slight in proportion to its size that the freezing of water in it does not break 45 it. The spring being arranged on the follower permits of slight variation in the adjustment of the cross-plate E without causing the follower to bind either on the walls of the packing-cavity or of the polished rod. 50

What I claim as new is—

A stuffing-box comprising the box proper having the packing-cavity and flanges extending therefrom, said flanges having perforations for the tightening-bolts; and braces extending from the flange to the walls of the box 55 adjacent to said perforations, the said braces stiffening the flange and locking the nuts of the tightening-bolts; a follower in said cavity; a coiled spring arranged on said follower and adapted to encircle a rod passing through 60 the stuffing-box; a cross-plate on the spring; and bolts extending through the cross-plates and through the perforations in the flanges, said bolt being provided with nuts which are 65 locked by braces on the flange.

In testimony whereof I have hereunto set my hand in the presence of two subscribing witnesses.

WILBUR C. NORRIS.
